UNITED STATES PATENT OFFICE.

EDWARD N. JACOBI, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

INSTRUMENT LIGHT.

Application filed March 3, 1920. Serial No. 363,035.

This invention has for its object to provide an instrument light for instrument panels of automobiles and the like.

An object of the invention is to simplify the construction of a lamp of this type for use with what is known as a two wire lighting system, in which a ground return is not employed.

Another object of the invention is to 10 avoid the use of coil springs of small diameter and to provide for housing a large coil spring in a space surrounding the lamp base, the shell providing such space affording a support for a hood or shield and 15 adapted to cooperate therewith for partly or completely masking the lamp when desired.

With the above and other objects in view 20 the invention consists in the instrument light as herein claimed and all equivalents.

Referring to the accompanying drawings in which like characters of reference indicate the same parts in different views:—

Fig. 1 is a central sectional view of an 25 instrument light constructed in accordance with this invention;

Fig. 2 is a similar view on a plane at right angles to the sectional plane of Fig. 1;

Fig. 3 is a transverse sectional view there- 30 of with the lamp removed;

Fig. 4 is a sectional view with the lamp removed; and,

Fig. 5 is a view in elevation.

In these drawings 10 indicates a plate 35 forming a support, such as the front plate of a panel board of an automobile instrument set. A sheet metal shell 11 passes through an opening in the plate 10 with its outwardly turned flange riveted to the edges 40 of the opening, together with an insulating base or end piece 12 of vulcanized fiber or other suitable material.

The upper end of the shell 11 is preferably reduced in diameter, as shown, and 45 seated against the shoulder formed by this reduction is a coil spring 13 bearing at its other end against an insulating spacing ring 14 which is carried by a longitudinally movable sleeve 15, constituting a socket for an electric lamp 16.

The sleeve 15 is provided with opposite bayonet slots 17 to receive the projecting pins or studs 18 of the usual lamp base 19

to make a spring-pressed locking engagement and electrical contact therewith.

The spacing ring 14 is held by an outwardly turned flange 20 at the lower edge of the sleeve 15 and a like flange 21 at the upper end of said sleeve similarly engages another spacing ring 22 of insulating material which fits within the guide formed by the reduced upper portion of the shell 11 and is held in place by outwardly bent lugs 23 cut from the sleeve. The sleeve is thus slidably mounted within the shell and is held downwardly with spring pressure, though it is spaced from the shell by insulating rings and is free from electrical contact therewith in all of its positions.

When the lamp 16 is inserted in the sleeve 15 with its lugs 18 fitting in the bayonet slots, its end terminal 24 bears on a contact 25 which is clinched to the center of the insulating end piece 12, and the lugs 18 co-operate with cam portions 26 of the bayonet slots 17 when the lamp is turned so as to lift the sleeve 15 against the pressure of its spring until the lugs enter the pockets in the ends of the bayonet slots. In this position the parts are held with spring pressure, insuring firm electrical contact between the lamp terminals and the socket terminals.

A tongue 27 projects from contact 25 through the insulating end piece 12 and a similar tongue 28 projects from the lower edge of sleeve 15 and slidably fits through an opening in the insulating end piece 12, and these tongues 27 and 28 form wiring connections to which the lead wires may be soldered or otherwise connected.

A metal hood 29 fits on the reduced portion of the shell 11 and the opening 30 in its side through which the light shows may be turned so as to be closed by an upwardly extending projection 31 on the edge of the shell, forming a shield to partly or entirely block the passage of light through the opening of the hood. This adjustment is effected by merely turning the hood.

The light of this invention is of simple construction that is inexpensive to manufacture and still is strong and durable, particularly because of the location of the spring in the space surrounding the lamp socket, thus enabling the use of a large spring that will not be liable to weaken.

The moving lamp socket sleeve is thoroughly insulated and the parts are held in firm electrical contact by the pressure of the spring.

5 The adjustable hood with its cooperating guard on the shell enables the light to be controlled as desired and the entire device is neat and ornamental in its appearance.

One of the principal uses for the invention is as a dashlight in series with the tail-light. In such arrangement it is necessary to provide for a wiring connection with both terminals of the dashlight even though the lighting system is of the single 10 wire type. The device of the present invention permits of the use of the single contact lamp standard with such systems and when it is desired to have the tail lamp burn without a material light on the dash, 15 the adjustment of the hood of this light permits thereof.

What I claim as new and desire to secure by Letters Patent is:—

1. An instrument light, comprising a 20 shell, a base having a contact for engagement by the end terminal of a lamp base, a longitudinally movable sleeve adapted to receive the lamp base, a spring urging the sleeve toward the base, and a tongue projecting from the sleeve and slidably passing through the base and adapted to form a 25 wiring connection.

2. In an instrument lamp, a shell, an insulating base therefor, a sleeve slidably 30 mounted within the shell and insulated therefrom, a spring urging the sleeve toward the base, a tongue projecting from the shell and slidably passing through an opening in the insulating base, said sleeve being 35 adapted to receive a lamp base, and a contact on the insulating base adapted to be engaged by the end terminal of the lamp base.

3. In an instrument light, a shell, a sleeve 40 within the shell, an insulating ring spacing the sleeve from the shell, a coil spring surrounding the sleeve and contained within

the space between the shell and the sleeve and bearing on the ring, and on the shell, 45 said sleeve being adapted to receive a lamp base, and an insulated contact at the end of the shell adapted to be engaged by the end terminal of the lamp base.

4. In an instrument light, a shell, a sleeve 50 within the shell, insulating rings surrounding the sleeve and spacing its ends from the shell, a coil spring surrounding the sleeve and contained within the space between the sleeve and the shell and bearing 55 on the shell and on one of the insulating rings, said sleeve being adapted to receive the base of an electric lamp, an insulating end piece on the shell, and a contact on the end piece adapted to be engaged by the end terminal of the lamp base.

5. In an instrument light, a shouldered shell, a cylindrical sleeve therein, insulating rings around the ends of the sleeve 60 spacing them from the walls of the shell, a spring surrounding the sleeve and seated on the shoulder of the shell and bearing 65 on one of the insulating rings, said sleeve having bayonet slots to receive the lugs of a lamp base, an insulating end piece on the shell, a contact thereon adapted to be 70 engaged by the end terminal of the lamp base, and a connecting tongue on the sleeve 75 passing through an opening in the insulating end piece.

6. In an instrument light, a sheet metal 80 shell with a reduced upper end forming a shoulder, a sleeve within the shell, a spring 85 surrounding the sleeve and bearing against the shoulder and adapted to move the sleeve downwardly, an insulating end piece on the shell, a contact thereon, said sleeve being adapted to receive a lamp base and the contact to engage the end terminal of the lamp base, the reduced end of the shell being 90 adapted to receive a hood fitting against the shoulder.

In testimony whereof, I affix my signature.

EDWARD N. JACOBI.
